PAGE 2

FIG. 3

FIG. 5

FIG. 4

FIG. 6

FIGURE 1 is a perspective view of my design for a portable stereo phonograph shown in a closed or carrying position;

FIGURE 2 is a top perspective view of my design shown partially opened;

FIGURE 3 is a perspective view of my design illustrated in a fully opened or playing position;

FIGURE 4 is a side elevational view of my design as seen in FIGURE 3; and

FIGURES 5 and 6 are side elevational and rear views respectively of my design as seen in FIGURE 1.

The bottom of my design is plain and unornamented.

The dominant features of my design reside in those portions of the drawing shown by means of full lines.

I claim:

The ornamental design for a portable stereo phonograph, substantially as shown and described.
